UNITED STATES PATENT OFFICE.

STANLEY GAUTEREAUX, OF LOS ANGELES, CALIFORNIA.

EXCAVATING APPARATUS.

1,415,544.

Specification of Letters Patent.

Patented May 9, 1922.

Application filed March 5, 1919. Serial No. 280,877.

To all whom it may concern:

Be it known that I, STANLEY GAUTEREAUX, a citizen of the United States, residing at Los Angeles, in the county of Los Angeles and State of California, have invented new and useful Improvements in Excavating Apparatus, of which the following is a specification.

My invention relates to improvements in apparatus for excavating ditches or trenches for irrigating and other purposes.

An object of the invention is to provide an excavator that will supply the demand and rapidly growing need for a more efficient means for the construction and formation of irrigating trenches and ditches; and while this excavator in its preferred form of construction is especially adapted for that purpose, it is not intended to limit it to any special class of excavating.

The irrigating trench forming industry has developed new requirements and conditions that the present equipment of obsolete and antiquated tools and machinery are not adequate to meet and perform; consequently the need and demand for an apparatus that can expeditiously and satisfactorily perform the necessary work within the time limit allotted to this labor; for limited time has become one of the vital features of this industry. Consequently there is a necessity for an apparatus that will travel over the irrigating course rapidly and effectively. Too great an emphasis cannot be placed on the feature of limited time when considered in relation to the irrigating trench construction, as many of these trenches must be formed in the time intervening between the harvesting of one crop and the planting of another, which means that every moment lost in trench forming for irrigating is a corresponding loss of growing time to the crop to be planted.

A feature of my invention is to provide novel means for forming the first or opening cut of the trench, which feature is useful, expedient and easy of operation.

Other features of my invention are to provide novel means for forming the subsequent cuts of the trench and means for removing the material from said cuts and discharging it to one side of the trench.

The features of having a plow in advance for forming a trench in which the lower end of a conveyor can move to carry away the soil, and another plow for turning a two

furrow-slices back into the conveyor; and the provision of rimless sprocket wheels in the conveyor so that the two furrow-slices can be more readily thrown into the conveyor; and also the feature of a single conveyor, inclined across the trench to locate its discharge end on one side of the trench, are in combination primarily new.

Other features of the invention are shown in the novel means employed for mounting in separate frames each unit of trench forming apparatus, and also the novel means employed to raise or lower any one of said frames separately or all together for the purpose of clearing away obstructions or for digging a deeper or shallower trench and also for the purpose of transportation from place to place; also the means for telescoping the axles so that for transportation the excavator can be narrowed to pass through narrow roads or gateways.

Other objects, advantages and features of invention may appear from the accompanying drawings, the detail description and the appended claims.

The accompanying drawings illustrate the invention:

Figure 1 is a side elevation of the excavator partly diagrammatically shown, immaterial detail being omitted on account of the small scale on which the figure is drawn.

Fig. 2 is a plan view of what is shown in Fig. 1.

Fig. 3 is a plan view of the excavator diagrammatically shown; and also showing a special means for propelling the excavator through exceedingly refractory material.

Fig. 4 is a section through the ground showing a trench for which the excavator is especially adapted for forming.

Fig. 5 is a central longitudinal view through the trench leveler that is attached to the excavator and drawn behind, as shown in Figs. 1 and 2.

Fig. 6 is a fragmentary part of the front end of the excavator showing the front truck and associated parts in side elevation.

Fig. 7 is a section taken on the line x^7-x^7 of Fig. 6 parts being omitted and parts being broken away, and the figure drawn to a larger scale.

Fig. 8 is a plan view of the mechanism shown in Fig. 6, parts being omitted and parts being broken away and parts being sectioned.

Fig. 9 is a section taken on the line x^9-x^9

of Fig. 8 showing the parts enlarged to the same scale as Fig. 7.

Fig. 10 is a broken fragmentary portion of the excavator shown in side elevation, 5 said portion being taken just to the rear of the portion of the excavator shown in Figs. 6 to 9 inclusive.

Fig. 11 is a plan view of what is shown in Fig. 10, parts broken away.

10 Fig. 12 is a side elevation of the sector and lever mechanism for controlling the upper ends of the plow beams; the view being taken on the line $x^{12}-x^{12}$ Fig. 11, parts being broken away and parts being omitted.

15 Fig. 13 is a section taken on the line $x^{13}-x^{13}$ of Fig. 12, parts being broken away.

30 Fig. 18 is a section on the line $x^{18}-x^{18}$ Fig. 16.

Fig. 19 is a section on the line $x^{19}-x^{19}$ of Fig. 1, on a larger scale and showing in 35 sectional plan view a part of the excavator that is in the rear of and joins to the part shown in Figs. 10 to 18 inclusive.

Fig. 20 is a plan view of the plows and bottom portion of the conveyor shown in Fig. 19, many parts being omitted for the 40 sake of clearness and the beams being shown in section.

Fig. 21 is a plan view of the advanced 45 or right hand plow shown in Fig. 19 entirely separated from its associated parts and the beam being shown in section.

Fig. 22 is a plan view of the rear or left hand plow shown in Fig. 19 entirely separated from its associated parts, and the beam being shown in section.

50 Fig. 23 is a section through a trench two furrows deep showing how the plow and conveyors shown in Fig. 20 would appear therein parts being omitted and broken away.

55 Fig. 24 is a central longitudinal sectional view of the conveyor shown in Figs. 19 to 23 inclusive, some of the associated parts being shown in perspective and parts being omitted and parts being broken away.

60 Fig. 25 is an enlarged detail view of the chain conveyor shown in Fig. 24.

Fig. 26 is a section taken on the line $x^{26}-x^{26}$ of Fig. 25.

65 Fig. 27 is a plan view of one of the rim less conveyor wheels shown in Fig. 25.

Fig. 28 is a section on the line $x^{28}-x^{28}$, Fig. 1 showing the means for driving the rimless conveyor wheels and also the means for raising and lowering the frames that have attached thereto the trench forming apparatus.

Fig. 29 is a section on the line $x^{29}-x^{29}$, Fig. 28, parts being omitted and parts being broken away; showing the ends of one of the frames on which the trench forming apparatus is mounted brought near together by breaking away the center portion of the frame, in order to show how the drums operating in pairs raise and lower these frames.

80 Fig. 30 is a section on the line $x^{30}-x^{30}$ Fig. 29, showing a pair of sheave pulleys and their mounting.

Fig. 31 is a slightly enlarged and reversed view of the lower left hand corner 85 of Fig. 28, parts broken away and omitted, showing in detail the attachment for connecting the cables to the bottom of the sliding frames.

Fig. 32 is a side elevation of the chain 90 tightener shown in Fig. 28, the chain and pinions being shown by dotted lines and also an altered position being shown by dotted lines.

Fig. 33 is a section taken on the line $x^{33}-x^{33}$ Fig. 29, parts omitted and parts broken away.

Fig. 34 is a plan view of what is shown in Fig. 33.

Fig. 35 is a section taken on the line $x^{35}-x^{35}$ Fig. 34, parts being broken away.

Fig. 36 is a section on the line $x^{36}-x^{36}$ Fig. 34, parts being broken away and parts being omitted.

Fig. 37 is a section on the line $x^{37}-x^{37}$ Fig. 33, parts omitted and parts broken away.

Fig. 38 is a vertical section through the main frame, the center of the cross plates being broken away and the uprights and the 110 longitudinal angle irons brought closer together.

Fig. 39 is a section on the line $x^{39}-x^{39}$ Fig. 38, showing how the upper cross plates and upper angle irons are riveted to the 115 lower flange of the upper longitudinal angle iron.

Fig. 40 is a section on the line $x^{40}-x^{40}$ Fig. 38, showing the intermediate cross plate riveted to the upright angle irons.

120 Fig. 41 is a central vertical section through one of the frames to which the excavating apparatus is attached, the apparatus being omitted.

Fig. 42 is an enlarged plan view of one 125 of the brackets for securing the upper corners of the frame shown in Fig. 41.

Fig. 43 is another view of the bracket above described.

Fig. 44 is an enlarged plan view of one of 130

the upper corners of the frame for carrying the excavating apparatus, the latter not being shown.

Fig. 45 is a section on the line $x^{45}-x^{45}$
5 Fig. 44, showing an inner view of the foregoing mentioned corner of said frame.

Fig. 46 is a section on the line $x^{46}-x^{46}$
Fig. 41, showing in detail, one of the lower corners of the sliding frames.

10 Fig. 47 is a section on the line $x^{47}-x^{47}$
Fig. 46, showing another view of the foregoing corner.

In detail, the main frame 1' of the excavator consists of pairs of lower longitudinal 15 angle irons or base plates 1 and upper longitudinal angle irons or plates 2 respectively, which are spaced apart in width by the cross pieces 3 and 4 spaced in height by a plurality of angle irons 5 which are 20 riveted to the cross pieces 3 and 4 and also the angle irons 1 and 2; also intermediate cross plates 6 are riveted to the upright angle irons 5.

At both the forward and rearward ends 25 the longitudinal angle irons are bent inwardly to form a narrower frame between the wheel bases of the excavator; and these bent in portions have additional cross pieces, plates and braces to form a substantial main, 30 frame.

At both the forward and rearward ends 35 of the angle irons 1 there is secured the cross pieces 7 having pivotally mounted therein the eye bolts 8 by which means the main frame is suspended between the wheel bases.

The wheel support for the main frame is substantially alike for both front and rear ends except that in position the steering 40 mechanism is reversed; so that the detail description of the wheel support of one end of the excavator will also describe the other.

The wheels 9 are mounted in the telescoping axle 10, which latter is secured centrally 45 in a spring supporting block 11. Between said block 11 and a plate 12 there are mounted the springs 13; and a bolt 14 which passes through the eyebolt 8 and block 11 and which straddles the telescoping axle 10, 50 has its ends secured to the plate 12 by which means the main frame is spring supported and suspended on said wheel base.

Pivoted on the eyebolt 8 is the segmental gear frame 15 which has its forward part 55 on the front end of the excavator connected by suitable means to a tongue 16, the tongue however, being omitted in the rear frame 15.

On the opposite side of the frame 15 from the position of the tongue 16 and integral 60 with said frame, is the segmental gear portion 17 that is in mesh with the pinion 18; and meshing with the face of the pinion 18 is the gear 19 secured to the steering post 20.

On the upper end of the steering post 20

is secured the steering hand wheel 21; and 65 suitably connected with one of the cross plates of the platform 22 is pivoted the dog 23 which has one end adapted to mesh with the gear 19 in order to hold it in any desired fixed position. 70

Integral with the frame 15 and on opposite sides thereof, and astride of the telescoping axle 10, are the upright arms 24 with their sides next to the axle 10 and bearing against the latter so that when the 75 frame 15 is turned by the steering mechanism consisting of segment 17, pinion 18, gear 19, steering post 20 and handwheel 21, two of the arms 24 will contact with the axle 10, on opposite sides thereof and thereby turn the wheels 9 in one direction; and when the steering wheel is reversed, the other two arms 24 will turn the axle 10 and wheels 9 in the other direction. 80

From the foregoing it can readily be seen 85 that the main frame is suspended from the front and rear axles and held by gravity in a balanced position so that the axles and wheels associated therewith are free to have a side rocking motion relative to said frame 90 whereby the excavator can be moved over uneven ground without the frame tilting from an upright vertical position; in other words, the pivoted U bolt connection between the trucks and frame and the heavier 95 weighted bottom of the frame enables the latter to maintain a balanced vertical position.

As seen in the drawings, the vertical angle irons 5 of the main frame are arranged in 100 two pairs and on opposite sides of the frame; and positioned so that the inner angle of each angle iron forms a corner of a rectangular space into which the frames 25, 111, 112, 113, and 114 are slidably fitted. 105 And these rectangular spaces are of increasing length from the front to the rear of the excavator, and consequently these frames are of relatively increasing length.

The frames 25, 111, 112, 113 and 114 are 110 formed with the bottom, top, and angle irons 26, 27 and 28 respectively; and also the upright angle irons 29 all of which have their ends riveted to corner brackets 30, 31 and 32 respectively so as to form a substantially 115 rigid frame, as shown in Figs. 40 to 46 inclusive.

As seen in Figs. 1, 2, 10, 11 and 15, the frame 25 nearest to the front trucks of the excavator, is provided with a combination 120 of trench forming apparatus that are adjustably mounted on said frame.

As shown in said figures, but best in Fig. 15, there is a pair of longitudinal plates 33 having their ends secured by bolts 34 to the 125 end plates 28 of the frame 25; and by means of a plurality of holes 35 spaced apart in the end plates 28, said plates 33 are adjust-

able relative to the space between them; said adjustment having for its object the forming of trenches of various widths.

Toward the forward end of the frame 5 25, and secured to the plates 33 by bolts 36 is a pair of spaced plates 37 having bolt holes 38 corresponding to similar bolt holes 39 in the plates 33; the purpose of said bolt holes being for the adjustment of parts as above 10 stated, for forming trenches of various widths.

Secured to the plates 37 by the bolts 40, are the short cross plates 41 by the crossing of which with the plates 37 a squared bearing surface is formed for the beams 42, on 15 the bottom end of which are mounted the coulters 43. The means stated for holding the coulter beams is relatively the same both at top and bottom; except that at the latter 20 place there is a cross plate 44 that is adjustably secured to the beams 42 by bolts 45; said plates 44 resting on plates 41 and limiting the downward movement of said coulter beams. All the plow, coulter and elevator 25 beams have a similar adjustable mounting.

In the rear of the coulters and near the center of the frame 25 are two other pairs of cross plates 46 having their ends secured with bolts 47 to the plates 26 of the frame 30 25; and by means of a plurality of spaced bolt holes 48 in the plates 26, said cross plates 46 are adjustable longitudinally of the excavator.

In the plates 33 are also bolt holes 48 so 35 spaced that when the plates 46, which have intermediate bolt holes 48' therein, are shifted, certain bolt holes 48 in the plates 33 are adapted to register with certain bolt holes 48' in the plates 46, which thus may 40 be secured in such registering positions by means of the bolts 47. The spacing between the holes 35 in the angle irons 28 corresponds to the spacing between the holes 48' in the plates 46, and the spacing between 45 the holes 48 in the angle irons 26 corresponds to the spacing between the holes 48 in the plates 33, so that the plates 46 may be adjusted to parallelism with the angle irons 28, and the plates 33 may be adjusted to 50 parallelism with the angle irons 26 and to positions at right angles to the angle irons 28 and the plates 46.

There are also two pairs of cross plates 49 which are secured by the bolts 50 to the 55 plates 46; the crossing of said plates 46 and 49 forming a square bearing for the bottom end of the plow beams 51 to which end the plows 51 and 52 are attached respectively. These plow beams and plows are limited in 60 their downward movement by the cross plates 44 that are secured to the beams 51 by the bolts 45.

As shown in Figs. 10 and 15, the plow 52 is a sufficient distance in advance of the 65 plow 53 for the former to throw its furrow-

slice directly on top of the furrow-slice to be cut and thrown by the latter, so that the plow 53 throws two furrow-slices out to one side of the trench, as indicated by the arrows in Fig. 10.

Following the plow 53 and to one side of the same is the deflecting scraper 54 that engages the material excavated by the plows 52 and 53 and removes it a considerable distance from the trench. This scraper is 75 mounted on the lower end of the vertical beams 55, which latter are slidably mounted at top and bottom in the squared bearing formed by the crossing of the plates 56 and 57 secured by bolts 58. The plates 57 are 80 secured by bolts 59 to the top and bottom plates 26 and 27 respectively of the frame 25. The plates 56 and 57 and the frame plates 26 and 27 have a plurality of spaced bolt holes 60 and 60' respectively for adjustment of the parts for the purpose aforementioned.

Secured to the plates 57 by the bolts 61 are the cross plates 62, the crossing of which forms a square bearing at both the 90 top and bottom of the excavator for the vertical beams 63, to the bottom end of which are secured the coulters 64.

Secured to the ends of the plates 26 of the frames 25 are the brackets 65 to which 95 is preferably secured the turn buckles 66, one end of which is attached to the cable 67; and these brackets 65, turn buckles 66 and ends of cable 67 are near to the lower corners of the frame 25.

Two of the cables 67 which are on one side of the frame 25 pass directly upward and are attached to the drums 68 on the shaft 69 by the set screws 70, as shown in Figs. 28 and 35. The other two cables 105 67 on the opposite side of the frame pass upward and over the sleeve pulleys 71 which are suitably mounted in the brackets 72 which latter are secured to the cross plates 6 of the main frame; and are thence extended across the upper part of the frame 25 to the drums 68, and are secured to the latter as are the other cable ends.

There are a plurality of the shafts 69 mounted end to end in the bearing blocks 115 73, as shown in Fig. 34, which bearings are secured to the plates 6 of the main frame, so that each shaft is free to rotate independently of the other; which independent movement enables any one of the frames 25, 111, 120 112, 113 and 114 to be raised or lowered separately or simultaneously.

This independent action of the frames is one of great utility, and great emphasis is placed on the importance of this feature of 125 the invention; as it is often necessary to stop the excavator and to elevate the excavating apparatus from the trench for the purpose of sharpening the digging points or replacing bent or broken ones.

- In trench forming, it is quite often the case that obstructions are encountered requiring manual means for their removal; such as rocks too large for the excavator to handle; in which case any one of the aforementioned frames may be elevated to a position which will give sufficient room for working to remove the obstruction without disturbing the other excavating apparatus.
- When the obstruction has been removed the elevated frame may be returned to its former position and the excavating operation resumed without having changed or altered the position of the other frames.
- This feature of the invention is especially advantageous when the trench is being constructed to a surveyed line and cut to a predetermined grade. It is also of great utility in preparing the excavator for transportation to other work when through at one place, as all the frames may be simultaneously elevated and the excavator moved away.

Integral with the drums 68 are the pinions 74, the latter having their teeth meshing with the teeth of the gears 75 which are loosely mounted on the shaft 76 each having extending from the side thereof the sleeve 77 mounted on the bearing 73 and provided with means for preventing movement longitudinal of the shaft 76, as shown in Figs. 35 and 36.

On the other side of each gear 75 and integral therewith is one member 78 of the clutch 79. The other member, 80, of the clutch 79 is mounted on the shaft 76, and the clutching members 78 and 80 are moved into and out of engagement by the bifurcated lever 81 which is fulcrumed on the pin 82, said pin passing through the extension 83 of the bearing 73. To one side of the lever 81 and integral therewith is the tooth 84 which is adapted to mesh with the saw tooth depressions 85 in the spring clasp 86, said clasp being secured to the bracket 73 and adapted to hold said lever in position when the clutch 79 is either in or out of clutching engagement, as shown in Figs. 32, 35, 36.

As seen in Figs. 1 and 2, the shaft 76 extends from near the forward end of the excavator throughout the series of frames 25, 111, 112, 113, and 114 to near the rear end.

The forward end of the shaft 76 is provided with the beveled gear 87 that meshes with the beveled gear 88 on the jack shaft 89 which shaft has its ends mounted in the bearings 90 and 91 respectively.

Secured to the jack shaft 89 is the sprocket wheel 92 which is connected by the chain 93 to a sprocket 94. The mounting of the sprocket wheel 94 is similar to the gear and clutch mounting as shown in Fig. 36; the sprocket wheel 94 being loose on the engine shaft 95 and operated by the lever and clutch mechanism 96.

The engine 97 may be of any standard type and mounted on the frame of the excavator in any desired manner.

Through the connection of the drums 68 to the engine 97 and the intervening clutch 70 means, any one or all of the frames 25, 111, 112, 113 and 114 and their attached excavating apparatus may be raised or lowered separately or simultaneously, the mechanism connecting each frame to the engine 75 being substantially the same.

As seen in Figs. 28 and 33, means is provided for holding each frame in an elevated position, consisting of a dog 98 which has one end pivoted on the pin 99 which is secured to the side of the bearing 73. The other end of the dog 98 has a tooth 100 which meshes with the teeth of the pinion 74 and thereby preventing the rotation of the drum 68 in the direction that would enable the frames to descend.

As the drum is revolved in the direction to elevate the frames, the teeth of the pinion 74 push the tooth out of engagement.

The dog 98 is held in engagement with the teeth of the pinion by the spring 101 so that the dog will automatically engage the succeeding teeth of the pinion 74 as it is rotated.

To hold the dog 98 entirely out of engagement with the pinion 79 there is provided the hand rod 102 which is pivotally connected to the toothed end of the dog 98 by the pin 103. To one side of the rod 102 and integral therewith is the latch 104 which, when the rod 102 is drawn downward to disengage the dog 98, is manually moved to the underside of the pin 105 which is secured in the plate 6.

As previously stated, any one or all of the frames may be raised or lowered separately or simultaneously and so maintained in any desired position, the reason for which has been fully explained. Attention is called, however, to the special construction of the parallel shafts 69 and 76 and their associated parts by means of which the raising and lowering of the frames separately and simultaneously is accomplished.

The shaft 69 is composed of a plurality of shafts placed end to end and held in that position by means of the bearing 73 fitting into the notched ends of the shafts thus preventing endwise movement.

On the gears 75 of the shaft 76 are sleeve extensions which have similar notched ends secured in the bearings 73, which mechanism in combination with the clutching means enables the shaft 76 to be used for driving the excavator and also for raising and lowering the drum and driving the conveyors.

Means for tilting the point of the plow-share so it will cut into refractory substances and not be deflected upward consist in a pair of guides 106 at the top of the frame 25 and secured to the longitudinal top plates 33,

- between which guides and the plates 33 there are slidably mounted the bearing plates 107 through which the upper ends of the plow beams 51 extend.
- 5 Pivottally connected to one end of each of the plates 107 are the rods 108 the other end of the rods being connected pivottally to the arm 108', as shown in Figs. 11 and 12, and controlled by the hand lever 109, which 10 lever is provided with a sector 109' and latch 109'' for holding the plates 107 in any desired position and consequently tilting the plow points to cut either deeper or shallower.

- 15 By moving the lever 109 either toward the front or rear of the excavator the upper ends of the plow beams 51 will also be moved and cause the plow points to be raised or lowered and thereby alter their cutting effect 20 in the ground.

- To the lower part of the plow beams 51 there may be secured one end of the chain 110 the other end of which may be secured to the longitudinal plates 33 to help resist 25 the backward thrust of the soil against the plows.

- In the rear of the frame 25 and its associated parts are the frames 111, 112, 113, and 114 which are substantially like the frame 25 30 except in length; and each of these frames are relatively longer from the front to the rear of the excavator; and the excavating mechanism in said frames is practically the same except that the elevator in each frame 35 is relatively of greater length. So a detailed description of one of these frames and its associated parts describes all the others; and the frame 111 and the mechanism with it will be described.

- 40 As shown in Figs. 1, 2, and 19 to 36 inclusive, the frame 111 is provided with longitudinal plates 115 at top and bottom which are adjustable sidewise of the excavator by bolts and a plurality of registering bolt holes 45 as in frame 25. The cross plates 116 have the same means for adjustment. Within the squares formed by the crossing of the plates 115, 116 and the plates 117 are the vertical beams 118 to which beams and the frame 50 plates the excavating apparatus is secured.

- Near the front of the frame 111 is the beam 118 to the lower end of which is secured the routers 119 immediately in the rear of which is the plow 120 which, as shown in Figs. 19 55 to 23 inclusive throws its furrow-slice directly on top of the furrow-slice of plow 121. This plow 121 throws the double furrow-slice thus formed back into the rear of plow 120 directly into the rimless sprocket wheel 60 122, as shown by the arrows in Figs. 19, 20 and 23.

- The sprocket wheel 122 is mounted in the lower end of the conveyor trough 123, which 65 extends upwardly and has its upper end slotted and slidably mounted on the pins

123' which are secured to the supports of the sprocket wheel 124. As shown in Fig. 24, the under portion of the trough 123 is cut away at the upper end to make a discharge port for the dirt.

70 On the rimless sprocket wheel 122 as well as on the rimless sprocket wheel 124 is mounted an endless conveyor 125 consisting of the chains 126 to which are secured the dirt removing disks 127, as shown in Figs. 75 to 27 inclusive.

The conveyor is driven by means of the shaft 128 one end of which is connected by the universal joint 129 to the shaft of the sprocket wheel 124, the other end having 80 the bevel pinion 130 which meshes with the gear 131 on the shaft 132. On said shaft 132 is mounted the clutch 133 and the sprocket wheel 134 which is connected with a sprocket wheel 135 on the shaft 76 by the 85 sprocket chain 136 to which is suitable connected a chain tightener 137 to hold it in the right working tension when the frame 111 is either raised or lowered.

By the means above mentioned the conveyor 125 is moved to elevate the material thrown up by the plows 120 and 121 and thrown into the rimless sprocket wheel 122 and onto the chains 126 and between the 95 disks 127.

As the conveyor 125 travels in the direction of the arrows, as shown in Fig. 24, the dirt or material from the double furrow is forced up the inclined trough 123 and discharged at the upper end of said trough and 100 to one side of the trench.

From the foregoing description of the construction and operation of the frame 111 and the fact that the excavating mechanism of the frames 112, 113 and 114 is substantially 105 like that of frame 111, it will be seen that the excavating apparatus of each of these frames will cut a trench two furrows wide and one furrow deep and discharge the excavated material to the side of the trench as 110 the excavator advances.

By the adjusting means of the frame plates heretofore described the excavators of each frame may be set so that the walls of each cut will be in the same vertical plane, or that the furrows will be of decreasing width and thereby form a trench similar to that shown in cross section in Fig. 4, in which are shown five different cuts, *a*, *b*, *c*, *d* and *e*.

115 As shown in Figs. 11, 29, 34 and 35, the drums 64 are in pairs, and of increased diameter from the front to the rear of the excavator in order to lift the excavating apparatus practically to the same level when the 120 excavator is to travel idle from place to place.

The drums 68 in the frame 25 being of less diameter than the drums 68 in the frame 111; and the drums 68 in the frame 111 be- 130

ing smaller than those in the frame 112; and the other drums being of relatively increasing size, the same rotation of the shaft 69 will lift these frames to relatively higher levels and thereby bring the excavating apparatus attached to each frame up to substantially the same level.

The excavating apparatus of each frame being relatively deeper in the trench from 10 the front to the rear of the machine, in operation, in order to lift these excavators clear of the trench and ground and bring them into alignment for travel from place to place, each pair of drums from the front to the rear 15 of the excavator must be of greater diameter.

As previously stated, the shaft 76 is driven by the engine 97; and owing to the structure of the clutch 79, this shaft may be run continuously to drive the conveyors 125 and also 20 to propel the excavator forward or backward.

The excavator is propelled by means of the gear 138 which meshes with a pinion 139 on the jack shaft 140 which is secured to the cross plate 6 at the rear of the excavator. This shaft 140 has near each end thereof the sprocket wheels 141 which are connected to the sprocket wheels 142 which are secured to the rear axles 10, as shown in Figs. 1 and 2.

30 By the above described means, the excavator may not only be propelled from place to place under its own power, but also for the formation of ordinary irrigation trenches. In the event, however, of unusually refractory material being encountered and consequently additional power is required to propel the excavator, a coupling ring 144 is provided at the forward end thereof to which a tractor may be attached, as shown in Figs.

40 1 and 2. Or a tongue 16 may be secured to the forward trucks to which horses or mules may be hitched, as shown in Figs. 6 to 9 inclusive. Where such additional power is not available, another means may be employed 45 which is diagrammatically shown in Fig. 3. The drum 146 is secured to the platform of the forward end of the excavator, and to the shaft of the drum 146 is secured the sprocket wheel 147 which is connected by a chain 148

50 to the sprocket wheel 149 on the engine shaft, said shaft being provided with the clutch 150, as shown in Figs. 1, 2, 3, 6, and 7.

A cable 151 secured at one end to another 55 152 passes thence to the forward end of the excavator through the pulley 153 and is coiled on the drum 146 from which the cable passes through the pulley 154 and back to the rear anchor 155.

60 By use of the above described means, a great amount of power is applied to the cable and the excavator moved forward or rearward. The ability of the excavator to be propelled rearwardly is of great utility in that it may be moved out of the way of ob-

structions to be removed by blasting or other means.

In order to leave the bottom of the trench level and of a smooth grade, a leveler or follower 156 is secured to the rear of the excavator by the means of the cable 157. The 70 follower 156 is a trough with open ends preferably made of sheet iron and substantially the width of the bottom cut in the trench. It is of considerable length and is provided with the discharge ports 158 in its bottom. 75 Being open at both ends, any high points of dirt in the trench will be cut off by the front end of the follower and pass into the follower; and should there be any low spots in the trench the dirt in the follower will drop 80 through the discharge ports 158, which, for the purpose of guiding the loosened material downwardly, are provided with downwardly converging edges, as shown in Fig. 5, and fill the depressions.

85 In operation, the excavator is propelled under its own power to the place where the trench or trenches are to be formed; in the meantime of course the frames carrying the excavating apparatus are elevated and held 90 clear of the ground by means of the dogs 98 engaging the pinion wheels 74 to keep the drums 68 from rotation.

When the excavator is in position to begin 95 the operation of trench digging, the clutches 79 are thrown into engagement and the dogs 98 released and the frames lowered to the ground under the retarding power of the engine. The clutches 79 are then disengaged so that the shaft 76 is free to rotate without 100 driving the drums 68; to thereby operate the conveyors 125 and to also propel the excavator forward.

Then the depth and width adjustment of each of the central excavating apparatus is 105 accomplished by the cross plate and bolt adjustments heretofore described; the engine is put into operation and the excavator propelled forward to form the trench.

The construction illustrated and described 110 may admit of changes and modifications, and I may make such changes without departing from the spirit of my invention.

I claim:

1. In an excavator, a frame; pairs of beams 115 spaced apart and mounted in said frame said beams adapted to move vertically independent of said frame; pairs of plows on the lower ends of said beams, said plows arranged so that one plow of each pair is in advance of the other; plates for limiting the movement of said beams; and a flexible connection between said plows and said frame.

2. In an excavator, a frame; pairs of beams spaced apart and perpendicular in 125 said frame said beams adapted to move vertical independently of said frame; pairs of plows on the lower ends of said beams said

plows arranged with one plow of each pair in advance of the other so that the advanced plow of each pair of plows throws its furrow-slice on tip of the furrow-slice of the 5 rear plow of such pair; and means for moving the upper ends of said beams to tilt the plows.

3. In an excavator, a main frame; other frames slidably mounted within said main 10 frame; beams slidably mounted within said other frames; excavating apparatus secured to one end of said beams and adapted to a forward and a tilting movement; a shaft mounted in said main frame; a countershaft 15 in said main frame for each of said other frames, said countershafts abutting end to end; a driving connection between said shaft and said countershafts; and a connection between said countershafts and said other 20 frames whereby the latter may be raised or lowered.

4. In an excavator, a main frame; other frames slidably mounted in said main frame and movable independent of one another; 25 beams slidably mounted in said other frames; excavating apparatus comprising plows, coulters and elevators secured to lower ends of said beams and adapted to a forward and a tilting movement; a shaft; a countershaft 30 for each of said other frames; drums on said countershaft; cables connecting said drums with said other frames; and a driving connection between said shaft and said countershafts for the purpose specified.

35 5. In an excavator, a main frame; other frames movably mounted in said main frame and movable independent of one another; beams mounted in said other frame; excavating apparatus comprising plows and cutters 40 arranged in pairs and elevators for removing dirt displaced by the plows and coulters that are mounted on lower ends of said beams and adapted to a forward and a tilting movement; a shaft; a plurality of countershafts; a drum and cable connection between each of said other frames and said countershafts; gear connection between said shaft and said countershafts; and clutches 45 for controlling said gear connection.

50 6. An excavator comprising a plurality of plows arranged in pairs and in spaced relation to one another; and rigidly secured upon beams mounted so as to be vertically adjustable in the excavator, the arrangement of the 55 plows being such that each pair of plows forms a two furrow trench one furrow deep and with the center of each trench of each pair of plows in vertical and longitudinal alignment.

60 7. An excavator comprising a plurality of plows arranged in pairs and in spaced relation to one another; and rigidly secured upon beams mounted so as to be vertically adjustable in the excavator, the arrangement of the 65 plows being such that each pair of plows

forms a two furrow trench one furrow deep and with the center of each trench of each pair of plows in vertical and longitudinal alignment; and means for adjusting said pairs of plows to form a trench of greater or 70 less width and depth.

8. An excavator comprising pairs of plows arranged with a forward and rear plow in each pair; and also arranged so that the forward plow of the pair at the front end of the 75 excavator throws its furrow-slice on top of the furrow-slice of the rear plow so that the rear plow of said pair throws a double furrow-slice out to the side of the excavator; and with the other pairs of plows arranged 80 so that the forward plow of each pair thereof throws its furrow-slice on top of the furrow-slice of the rear plow of said other pairs so that the rear plows throw a double furrow-slice toward the furrows of the forward plows of said other pairs and into conveyors arranged behind each of said other 85 pairs of plows.

9. In an excavator, the combination of 90 traction wheels; axles mounted in said wheels; spring mounted bearings connected to said axles; a frame having longitudinal base plates positioned below said axles; an excavating apparatus mounted in said frame, said excavating apparatus having its heaviest portion positioned near said base plates; 95 and a pivoted connection between said frame and said axles whereby the equilibrium of said frame will be maintained.

10. In an excavator, the combination of 100 traction wheels; axles mounted in said wheels; spring mounted bearings connected to said axles; a frame having longitudinal base plates positioned below said axles; steering apparatus on said frame for guiding said axles; excavating apparatus mounted in said frame and having its heaviest portion positioned near to a center between 105 said base plates; a pivoted connection between said frame and said axles whereby 110 the equilibrium of said frame will be maintained; and means for moving the excavator, for the purpose specified.

11. In an excavator the combination of a 115 frame having excavating apparatus mounted therein; axles; traction wheels on the axles; sleeves on the axles, in which sleeves said axles are adjustably mounted so that said axles may be lengthened or shortened relative to the width of said excavator; a 120 pivoted connection between the frame and said sleeves whereby the axles may be swung to different positions; a steering apparatus for swinging the axles to the different positions; and means for moving said excavator, 125 for the purpose specified.

12. In an excavator, the combination with a main frame, of traction wheels; axles in the wheels; spring supported bearings pivotally connecting said main frame and said 130

axles; other frames mounted so as to be vertically movable within said main frame; trench forming plows and conveyors rigidly and operably mounted in said other frames; 5 and means for moving said excavator to form a trench.

13. In an excavator, the combination with a main frame, of traction wheels; axles in said wheels; spring supported bearings piv- 10 otally connecting said main frame and said axles; steering apparatus adapted to swing said axles; other frames mounted so as to be vertically movable within said main frame; trench forming plows and conveyors rig- 15 idly mounted in said other frames; a shaft mounted on the main frame; a connection between the conveyors of said other frames and said shaft; and means for driving said shaft.

20 14. In an excavator, the combination of a main frame; other frames movably mounted within said main frame; excavating apparatus mounted in said other frames; a shaft mounted in the main frame; a countershaft 25 in said main frame; means for driving said shaft; a rotating connection between the shaft and the countershaft; a connection between said countershaft and said other frames whereby the said countershaft may be moved; 30 and means for moving said excavator, for the purpose specified.

15. In an excavator, the combination with a main frame, of other frames movably mounted within said main frame; excavat- 35 ing apparatus mounted in said other frames; a shaft mounted in the main frame; a coun- 40 tershaft in said main frame; means for driv- 45 ing said shaft; a rotating connecting be- 50 tween said shaft and said countershaft; a cable and drum connection between the countershaft and said other frames whereby the latter may be raised and lowered; means for stabilizing the excavating apparatus; and means for moving said excavator, for 55 the purpose specified.

16. In an excavator, the combination with a main frame, of other frames mounted within said main frame; excavating apparatus mounted in said other frames; a shaft 50 mounted in said main frame; a countershaft in said main frame; means for driving said shaft; a gear and pinion connection between said shaft and said countershaft; a cable 55 and drum connection between said counter- 60 shaft and said other frames whereby the other frames may be raised or lowered; means for stabilizing the excavating apparatus; means for raising and lowering each of said other frames separately or simultane- 65 ously; and means for moving said excavator, for the purpose specified.

17. In an excavator, the combination with a main frame, of other frames mounted within said main frame; excavating apparatus 65 mounted in said other frames; a shaft

mounted in said main frame; countershafts in said main frame; means for driving said shaft; a gear and pinion connection be- 70 tween said shaft and said countershafts; a cable and drum connection between said countershafts and said other frames whereby the other frames may be raised or lowered; means for stabilizing the excavating appa- 75 ratus; means for raising and lowering each of said other frames separately or simultane- 80 ously; means for holding one or all of the said other frames in an elevated position; and means for moving said excavator, for the purpose specified.

18. In an excavator, the combination with a main frame, of other frames mounted within said main frame; excavating apparatus mounted in said other frames; a shaft mounted in said main frame; countershafts in said main frame; means for driving said 85 shaft; gear and pinion connections between said shaft and said countershafts; clutches on said shaft controlling said connections whereby said shaft may be driven independ- 90 ently of said countershafts; drums on said countershafts; cables connecting said drums with said other frames whereby said frames may be raised and lowered; means for stab- 95 ilizing the excavating apparatus and means for moving said excavator, for the purpose specified.

19. In an excavator, the combination with a main frame, of other frames mounted within said main frame; excavating apparatus mounted in said other frames; a shaft 100 mounted in said main frame; countershafts in said main frame; means for driving said shaft; a gear and pinion connection between the shaft and the countershafts; drums on 105 said countershafts, said drums being in pairs and each pair increasing in diametrical size, from the forward to the rearward ends of the excavator; and cables connecting each pair of said drums with one of said other frames whereby the increasing diameter of 110 each pair of drums will be the means of rais- 115 ing said other frames to relatively increasing higher planes thereby bringing the bottom part of said excavating apparatus into edge alignment when said other frames are ele- 120 vated; means for stabilizing the excavating apparatus and means for operating said ex- 125 cavator.

20. An excavator comprising a main frame, other frames slidably mounted in said main frame, pairs of plows in each of said other frames, coulters in each of said other frames for cutting straight edges in advance of said pairs of plows, conveyors for removing dirt displaced by pairs of plows rearward of the 125 first pair of plows, said conveyors inclined outward from the longitudinal axis toward the side of said main frame, an engine in said main frame, a shaft in said main frame, a driving connection between said engine and 130

said shaft, a counter shaft for each of said other frames, said counter shafts abutting end to end, a driving connection between said shaft and said counter shaft, and a 5 driving connection between said counter shafts and said conveyors.

21. In an excavator, a main frame; an engine in said main frame; a shaft in said main frame; a driving connection between 10 said engine and said shaft; other frames in said main frame; plows in said other frames; countershafts in each of said other frames, said countershafts paralleling said shaft; pinions on each of said countershafts; abutting sleeves on said shaft; gears on said sleeves engaging said pinions; and a clutch connection between said sleeves and said shaft for the purpose of operating the excavating apparatus independently. 15

22. In an excavator, the combination with a main frame, of other frames mounted within said main frame; a pair of excavating plows mounted in said other frames; means for operating said plows separately in pairs 25 or together, a pair of coulters mounted on each of said other frames in advance of each pair of plows, said coulters being formed to cut a straight edge substantially the width of the trench to be constructed; and means for 30 operating the excavators to form a trench.

23. In an excavator, the combination of a main frame; other frames mounted within said main frame; excavating apparatus mounted within said other frames; traction 35 wheels having telescoping axles supporting the main frame; means for securing said telescoping axles to adjust the wheels to a wide or narrow tread; means for operating the excavator to form a trench; and means 40 for depositing the excavated material to one side of said trench and between said trench and said wheels.

24. In an excavator, a frame; excavating apparatus mounted in said frame; means for 45 operating said excavating apparatus to form a trench; and a follower secured to said excavator and adapted to move over the bottom of said trench to gather the material

from the high places, the bottom of said follower being provided with openings 50 through which the gathered material may drop to fill any depressions in said trench bottom.

25. An excavator comprising front and rear axles, traction wheels on said axles, a 55 main frame suspended from said axles in a balanced position, a sliding frame at the forward end of said main frame, a pair of plows mounted in said sliding frame said plows arranged with one in advance of the other so that the advanced plow throws its furrow-slice on top of the furrow-slice of the rear plow and so the rear plow throws a double furrow-slice out to the side of the excavators, other sliding frames in said 60 main frame to the rear of the first mentioned sliding frame, a pair of plows in each of said other frames said pairs of plows arranged with one plow of each pair in advance of the other plow so that the advance 70 plow of said pair throws its furrow-slice on top of the furrow-slice of the rear plow so that the rear plow of each pair of plows in said other frames throws a double furrow-slice toward the furrows of the forward 75 plows, coulters arranged in all of said sliding frames for cutting straight edges in advance of each pair of plows, conveyors in each of said other frames for receiving the double furrow-slices thrown by the rear 80 plows said conveyors mounted on rimless sprocket wheels and inclined outwardly from the longitudinal axis toward the side of the main frames in position to discharge the dirt from the rear of said pairs of plows on 85 top of the double furrow-slice displaced by the first mentioned pair of plows, and means for propelling the excavator and operating said conveyors.

In testimony whereof, I have hereunto set 90 my hand at Los Angeles, California, this 27th day of February, 1919.

STANLEY GAUTEREAUX.

Witnesses:

WILLIAM M. GENTLE,
JAMES R. TOWNSEND.

Certificate of Correction.

It is hereby certified that in Letters Patent No. 1,415,544, granted May 9, 1922, upon the application of Standley Gautereaux, of Los Angeles, California, for an improvement in "Excavating Apparatus," errors appear in the printed specification requiring correction as follows: Page 7, line 53, for the word "another" read *an anchor*; page 8, line 4, claim 2, for the word "tip" read *top*; and that the said Letters Patent should be read with these corrections therein that the same may conform to the record of the case in the Patent Office.

Signed and sealed this 27th day of June, A. D., 1922.

[**SEAL.**]

KARL FENNING,

Acting Commissioner of Patents.
